PAPER BAG

Paul Arzet, Shelbyville, Ind., assignor to The Kennedy Car Liner and Bag Co., Shelbyville, Ind., a corporation of Indiana

Application April 9, 1934, Serial No. 719,780

3 Claims. (Cl. 229—58)

This invention relates to improvements in paper bags of the square bottom type.

It has for its general object the provision of a bag of the square bottomed type which will definitely assume its square form when expanded in the usual way by air pressure or by pressure of the hand against the inside of the bottom.

Another object of the invention is to provide a square bottomed bag in which opposite areas between the diagonals of the bottom are of multiply construction and triangular shape, affording stiff edges defining the diagonals of the bottom and the opposite sides of its perimeter whereby the bag unfolds definitely along the sides of these stiff areas in assuming its square expanded shape.

A further object of the invention is the provision of a bag folded as above described in which certain of the triangular multiplies are pasted together externally of the bag, stiffening the triangular areas and at the same time avoiding the presence of paste on the inside of the bag.

Still another object of the invention is to provide a bridging seam or strip of plural thickness extending along the altitudes of the stiffened triangular areas and across the apex or point of intersection of the diagonals of the bottom whereby an exceedingly strong reinforcement for the bottom of the bag is provided.

Other objects of the invention will appear as the following description of a preferred and practical embodiment thereof proceeds.

In the drawings which accompany and form a part of the following specification and throughout the several figures of which the same characters of reference have been employed to designate identical parts:

Figure 1 is a plan view of the blank indicating the several lines of fold;

Figure 2 is a perspective view of one end of the blank folded to form a plicated tube;

Figure 3 is a perspective view indicating the re-entrant pleats or folds;

Figure 4 is a perspective view showing the plicated tube folded flat;

Figures 5, 6, 7, 8, 9 and 10 are perspective views showing successive steps in the folding;

Figure 11 is a section taken along the line 11—11 of Figure 10; and

Figure 12 is a perspective view of the bottom of the bag in expanded condition.

Referring now in detail to the several figures the numeral 1 represents a blank which is creased longitudinally as shown defining lines of fold 2 and having longitudinal edges 3 and 4 adapted to overlap and being adhesively joined forming a

tube 18 such as is shown in Figure 2. Other longitudinal creases 5 define the apices of re-entrant dihedral angles 6, 7, 8 and 9 when the tube is folded as diagrammatically indicated in Figure 3.

The blank is also formed with a transverse crease 11 which defines the perimeter of the bottom when the bag is formed, and a transverse crease 12 which defines a margin 13 forming the bridging seam which extends across the bottom of the finished bag.

At any suitable time during the manufacture of the bag adhesive is applied to the stippled areas 14 and 15 on one side of the blank, to the stippled portions 16 and 17 of the margin 13 and throughout the entire length of the margin 13 on the reverse side.

The plicated tube 18 is folded flat as shown in Figure 4, the angles 6 and 7 becoming 180° angles and the angles 8 and 9 zero angles. With the tube 18 in this form, the margin 13 is folded over as shown in Figure 5 and adhesively united both inside, and to the side of the bag against which it is folded. The finger is then inserted between the laps of the zero angle 8 and the laps spread apart as indicated in Fig. 6 until the lower lap can be folded along a line 19 extending at an angle 45° to the edge of the folded margin 13. With the fingers still inserted between laps of the angle 8, the portion 20 of the margin which unites the laps of the angle 8 is swung over until it assumes a position against the bag perpendicular to the edge of the remaining portion of the margin 13. When the marginal portion 20 is pressed flat against the bag as shown in Figure 7, the line 21 along which the upper lap of the angle 8 folds will rest upon the bag at an angle of 45° to the bottom edge of the bag. When the bag is thus partially folded, it is inverted as shown in Figure 8. The fingers are next inserted between the laps of the zero angle 9, and the laps of said angle are spread apart as indicated in Figure 9.

The lower lap is folded upward along a line coincident with the line of fold 21 on the opposite side of the bag and the portion of the margin 13 swings over into a flat position against the bag opposite to and congruent with the portion 20. In the course of this manipulation the upper lap folds along the line 22 which arranges itself coincident with the line 19 on the opposite side of the bag. The appearance of the bag thus folded as shown in Figure 10, the bottom coming to a point and the laps of the angles 8 and 9 being firmly united to the sides of the bag which they overlie by means of the adhesive illustrated in the areas 14 and 15 in Figure 1.

The back folding of the laps of the angles 9 and 10 produce new angles 23 and 24 which when the bag is opened expand into angles of 180° permitting an outward buckling of the apical edges of said angles at the points 25 where the longitudinal creases 5 are intersected by the transverse crease 10.

Simultaneously with the buckling of the apices of the dihedral angles 23 and 24, the angles 8 and 9 which have now become 180° angles also buckle outwardly in their dihedral apices at corresponding points 25 permitting the bottom of the bag to assume the square form shown in Figure 12.

15 It will be understood that the multi-ply triangular areas 26 and 27 which appear on the outside of the folded bag as a result of the above described sequence of folding operations comprise three plies of material, one ply being the overlain portion of the side 28 of the bag and to which the triangular area is adhesively united. The triangular area itself consists of two plies which are open on the inside of the bag. The opposite side of the bag from that shown in Figure 10 is of similar construction. These areas define stiff opposite portions of the bottom of the bag, the bases of said triangular areas determining the periphery of the square bottom while the sides of said triangular areas determine the diagonals of the square bottom. The margin 13 is of 4-ply construction, the plies being adhesively united and the margin as a whole being adhesively united to the material which it superposes. This, in the expanded bag gives an extremely strong bridging member extending transversely of the bottom of the bag and adjacent the apex of fold determined by the intersecting axes of the bottom.

On account of the stiff triangular areas as described, this bag may be flipped open by atmospheric pressure in customary manner with the assurance of the bottom of the bag assuming a flat and square shape regardless of the size of the bag or the heaviness of the material of which it is constructed.

Furthermore, on account of the multi-ply thickness of the opposite triangular areas and the plural ply nature of the marginal strip which bridges them, an extremely strong construction is produced.

While I have in the above description painstakingly shown the method of folding this bag

by hand, it is of course understood to be amenable to manufacture by suitable machinery.

What I claim is:

1. Bag comprising a tubular member re-entrantly folded at opposite sides to form longitudinal dihedral angles the sides of which are double folds, the bottom of said tubular member being closed by a folded seam derived from the end margins of all plies of said member, secured together and to the portion of the bag which said seam overlaps, said seam closing the lower ends of the said dihedral angles, the front and back of the bag being formed by the flatly opened inner faces of the respective dihedral angles, and substantially triangular double ply reinforcements congruent with that part of the front and back of the bag which will be part of the bottom when the bag is expanded, and adherent thereto, said triangular reinforcements being derived from the lower corner portions of the sides of the respective dihedral angles adjacent the closed ends, said corner portions being opened out so that the closed ends of the dihedral angles have become the altitudes of the respective triangular reinforcements.

2. Bag comprising a plicated tubular member with integral square bottom when expanded, said bottom having triangular areas defined by intersecting diagonal creases, one pair of oppositely disposed triangular areas being of multi-ply construction with certain of said plies pasted together, said multi-ply triangular areas constituting reinforcements the sides of which form stiff delineations for determining the square shape of the bottom when the bag is expanded.

3. Bag comprising a plicated tubular member with integral square bottom when expanded, said bottom having triangular areas defined by intersecting diagonal creases, one pair of oppositely disposed triangular areas being of multi-ply construction with certain of said plies pasted together, said multi-ply triangular areas constituting reinforcements the sides of which form stiff delineations for determining the square shape of the bottom when the bag is expanded, said tubular member being closed by an end seam which in the expanded state of the bag extends continuously across the square bottom along the altitudes of the triangular reinforcements, and being pasted to the surface which it contacts.

PAUL ARZET.
